Filed June 29, 1962, Ser. No. 206,238
5 Claims. (Cl. 112—113)

This invention relates to a sewing or stitching apparatus, and more particularly to an automatic stitching apparatus for performing spaced stitching operations at predetermined points along the length of a garment.

This invention is a continuation-in-part of application Serial No. 68,515, filed November 10, 1960.

In the aforesaid application, there is disclosed a stitching apparatus having a movable garment carrier or carriage associated therewith. The garment on which the stitching operation is to be performed is clamped to the carriage, and the latter is advanced progressively and automatically beneath the needle of the stitching or sewing machine, mechanism being provided for stopping the carriage at a desired position and activating the sewing machine while the movement of the carriage is thus arrested. At the completion of a stitching cycle, the carriage is released for travel to the next stitching position.

The present invention relates to improved actuator mechanism resulting in smoother operation of the apparatus and accurate coordination of the various operations performed.

As will be more fully appreciated from the succeeding description, the successful operation of the device of the above mentioned application, as well as that of the instant application, is dependent upon the accurate timing of the distinct operations, namely, the arresting of motion of the carriage, the engagement of the presser foot of the sewing machine with the garment, and the initiation of the sewing cycle. In the device of the aforementioned application, careful adjustment of the apparatus was required to assure that the operations above noted were effected accurately and in the order specified.

Also, misuse by the operator of the above noted device could, in time, result in a loss of adjustment of the device whereby, in certain instances, the sewing cycle may be initiated prior to the operation of the work clamp. In such case, there is likely to be an improper attachment of a button and also it is possible for the sewing machine needle to break, with possible dangerous consequences.

The present invention accordingly has for an object the provision of an improved automatic stitching apparatus wherein the sequence of operation of the components is accurately and controllably timed.

A further object of the invention is the provision of improved, pneumatically actuated timing apparatus for an automatic stitching device.

Further objects will appear in conjunction with the following description of the drawings, in which:

FIGURE 1 is a perspective view of a sewing machine and feeder and garment positioner attachment secured thereto;

FIGURES 2 and 3 are magnified end elevational views of an escapement mechanism for controlling the position of the work holding carriage;

FIGURES 4 and 5 are plan views of said work holding mechanism, corresponding in positions respectively to the positions shown in FIGURES 2 and 3;

2

FIGURE 6 is a schematic diagram of the actuator mechanism for the work holder carriage and presser foot assembly of the sewing machine;

FIGURE 7 is a partially diagrammatic view of the sewing machine stitch cam mechanism, showing the interrelationship of said mechanism with the actuator mechanism.

In FIGURE 1 there is shown an automatic stitching apparatus in accordance with the invention. Details of such apparatus are fully set forth in the aforementioned copending application and will not be here repeated except to the extent necessary for an understanding of the present invention.

As shown in said FIGURE 1, 10 represents a conventional button sewing device to which is attached a button sorting and feeding assembly 11. The sewing device 10 and sorter and feeder assembly 11 are supported on work table 12, on which table there is mounted shiftable carriage assembly 13. The carriage includes clamps 14, 15, within which the garment is held to be supported preferably in taut condition. The carriage is operatively associated with a spring motor 16 fixed to table 12, the motor serving to return or advance the carriage longitudinally to the right as viewed in FIGURE 1 when the latter has been moved to its left-handmost position.

In the course of such return movement, stops 20, adjustably mounted on spacer rod 21, are progressively engaged by arrester and actuator mechanism 30 fixed to table 12, which mechanism stops the carriage at a desired position. The interengagement of the stops with portions of the mechanism 30 trips mechanism (hereinafter described in detail), which actuates the presser foot or work clamp 40, to clamp the garment against platen 41 of the sewing machine. The machine 10 is then actuated to perform a stitching cycle to secure a button held in the clamp 40 to the garment. It is important that the stitching cycle be initiated after the work clamp has been actuated to engage the work and it is to the mechanism for assuring accurate coordination of these steps that this invention is primarily directed.

As best seen in FIGURES 2, 3, 4, 5, and as fully described in the aforesaid copending application, the stops 20, in the course of the movement aforesaid, engage against actuator lever 50, which is horizontally and vertically pivotable and which normally lies in the path of movement of the stops 20.

The forward end of lever 50 is shifted to the right as viewed in FIGURES 2 and 3, causing lever 50 to pivot in a horizontal plane about pin 51, on which it is mounted with clearance, thus urging the stem 52 of control valve 52a inwardly or to the left as viewed in FIGURES 4 and 5. The tripping of stem 52 of valve 52a, through mechanism, hereinafter described in detail, causes the presser foot or work clamp 40 to descend, clamping the garment against the platen 41 of the sewing machine. The downwardly moving presser foot carries abutment means, not shown, which in the course of such downward movement strikes the upper end of vertically disposed stud 54, carried by lever 50, thus tilting the forward end 55 of said lever upwardly about pin 51 as a pivot, and raising said end 55 clear of the stop 20. As end 55 is cleared from the stop 20, finger 56 of restrainer arm 57 is shifted downwardly into the path of stop 20 and serves to hold the stop against further movement. The mechanism for causing the depression of finger 56

being fully described in the copending application, is discussed only briefly here to the extent required for an understanding of the improvement. To aid in such understanding, it should be observed that FIGURE 2 represents the position of the parts during a sewing cycle and that when the presser foot 40 is raised at the end of such sewing cycle, finger 56 is raised clear of the stops 20. In the meantime, the forward end 55 of lever 50 is positioned, as shown in FIGURE 3, above the stop 20, which engages the latter to initiate the stitching cycle, and when the carriage and stop 20 are permitted to continue to move by the raising of finger 56, the end 55 is spring urged downwardly into the path of the next succeeding stop.

Thus, the elements 55 and 56 act as an escapement, the element 55 first holding the stop 20 until element 56 is depressed by the downward movement of the work clamp. At release of element 56, element 55 engages behind the stop and is in position to receive the next stop.

The mechanism next to be described controls the escapement and presser foot. It should be understood that such control mechanism is not limited to use in conjunction with the specific escapement mechanism herein illustrated and described.

In FIGURE 6 there is schematically illustrated the control mechanism aforesaid. Control valve 53, which is of known construction, is provided with a piston or spool 60 which is shiftable to limiting positions, respectively, adjacent end 61 or end 62 of the valve. The ends 61, 62 are provided with bleed passages 63, 64, the passage 64 being closed by normally shut bleed valve 66. The passage 63, which is extended by conduit 63a, includes at the end of said conduit the normally closed bleed valve 52a. A source of air under pressure is introduced into the interior of valve 53 at points 67, 68, located, respectively, in chambers 53a and 53b of valve 53. It will be recognized that the pressure to each side of spool 60 will be equalized when bleed passages 63, 64 are closed and the spool thus will be held in equilibrium, but that when either passage 63 or 64 is opened to the atmosphere by the opening of valve 52a or 66a, respectively, that the chamber 53a or 53b which is opened to the atmosphere will be at a lesser pressure than the closed chamber and, thus, the spool 60 will be urged toward end 61 or 62 of valve 53, dependent upon whether valve 52a or 66a has been opened.

The air source in line P is communicated with the bore of valve 53 at point 70. An exhaust line E is similarly communicated with the bore at a point 71 spaced from point 70. Output lines I and K are similarly communicated with the bore of valve 53 at spaced points. The valve spool 60, on the outer periphery thereof, is grooved or recessed in known manner, said grooving functioning when the spool is shifted to a position adjacent end 61 of the valve to communicate pressure line P with line I, and exhaust line E with line K. Conversely, when the spool 60 is shifted to a position adjacent end 62 of the valve, pressure line P is connected to line K and exhaust line E to line I.

Lines I and K lead, respectively, to the upper and lower chambers 80, 81 of operating cylinder 82, said chambers being defined and separated by reciprocable piston 83. A regulator valve 84 is interposed in line I for purposes which appear hereafter.

The piston 83 of cylinder 82 is operably connected, as by chain 85, to the clutch lever 86 of the button sewing machine. A microswitch 87, in the normal (raised) position of the lever 86 is maintained in "open" position—that is, the contacts 88, 89 are separated. The microswitch 87 is connected in series with a source of power and with solenoid 90, which solenoid controls the operation of valve 91.

Armature 92 of solenoid 90 is operatively connected with spool 93 reciprocal in the said valve 91. Pressure and exhaust lines P and E, respectively, are com-

municated with the bore of the valve. Lines L and M lead from the valve 91 to the opposite chambers 95, 96 of presser foot control cylinder 97.

The spool 93 is grooved in known manner at its outer periphery so that when the spool is raised in valve 91 by energization of the solenoid 90, line M is connected to pressure line P and line L to exhaust E. When the spool 93 is in its normal (lowermost) position in said valve, to which it is urged by spring 94, line L is connected to pressure line P and line M to exhaust line E.

The chambers 95, 96 of cylinder 97 are separated and defined by piston 98 reciprocal in said cylinder, which piston is operably connected to the presser foot by presser foot operative lever 99.

The sewing machine 10 on the stitch cam 100 thereof is provided with a plurality of protruding cam elements 101. In the sewing machine illustrated, the cam 100 rotates 180° in the performance of one stitching operation although it should be understood that in other machines the angular distance of rotation of the cam may vary. The elements 101 are thus positioned about 180° angularly separated from each other. The elements include leading cam slope portions 102.

The bleed valve 66a of control valve 53 is connected by conduit O to chamber 53b of said valve. As seen in FIGURE 7, the valve 66a is secured by bracket 103 adjacent the stitch cam 100 and in the path of elements 101, it being understood that as elements 101 pass adjacent the valve 66a, the stem 66 thereof is depressed or opened, communicating temporarily the chamber 53b with the atmosphere.

The operation of the device is as follows: A garment is positioned in taut condition between holding clamps 14, 15, and the carriage 13 shifted to the leftwardmost

position as shown in FIGURE 1. The carriage is then released by the operator and carried by spring motor 16 toward its right hand position. As the first (righthandmost) stop 20 engages nose 55 of lever 50, the latter is pivoted horizontally (counter-clockwise as shown in FIGURE 4), a rearward portion of said lever tripping or depressing stem 52 or bleed valve 52a. Spool 60 of valve 53 is thereby shifted toward end 61 of said valve, communicating pressure line P with line I leading to chamber 80 of cylinder 82. The passage of air through line I is regulable by adjustment of valve 84, it being desired that a gradual downward movement of piston 83 be obtained rather than a ballistic or sudden movement. The movement of said piston downwardly in cylinder 82 depresses clutch lever 86, which, as is well known, must be shifted a considerable distance prior to triggering the sewing machine to start a sewing cycle. The lever thus may be described as at an inoperative position when it is raised, at an intermediate or neutral position when it has been depressed from the inoperative position but not to a degree necessary to trigger the sewing machine, and at an operative position when the lever has been depressed sufficiently to trigger the sewing machine.

As the lever 86 is drawn gradually downwardly, and at an early stage in such downward movement, moving contact 88 of microswitch 87 is engaged with contact 89, closing the circuit through solenoid 90. It is to be observed that the location of microswitch 87 and the gradual admission of air to cylinder 82 act to assure that the solenoid 90 will be energized a time period considerably preceding the initiation of a stitching cycle. If desired, mechanical means, such as a buffer spring or the like, may be utilized to slow the progress of the clutch lever 86, further to delay the actuation of the latter.

With the energization of solenoid 90, armature 92 thereof is lifted, carrying therewith the spool 93, whereby air is admitted through line P to line M, causing the piston 98 of cylinder 97 to rise abruptly and lowering the presser foot against the work. The presser foot is connected to a forward extension of pivoted lever 99, the rear end of lever 99 being moved with the piston 98. As is clearly

shown in FIGURE 1, when the rear end of lever 99 is lifted, the forward end is depressed, and thus depresses the presser foot.

It will be understood that the initial movement of stop 20 against lever 50 arrests movement of the carriage 13, and that when the presser foot 40 descends, as above noted, the finger 56 of lever 57 is depressed into the path of stop 20, holding the latter during the sewing cycle. The forward end 55 of lever 50 is simultaneously pivoted upwardly clear of the top 29 and will drop behind said stop in position to react to the next succeeding stop.

Subsequent to the depression of the presser foot in the manner aforesaid, the completed actuation of the sewing machine clutch lever begins a sewing cycle, and a button gripped adjacent the presser foot is stitched to the garment.

The stitch cam 100 meanwhile is rotated by the known mechanism of the sewing machine during the stitching cycle and one of the protruding cam elements 101 depresses bleed valve 66a in timed relation to the completion of the stitching operation. The opening of bleed valve 66a results in a shifting of spool 60 of valve 53 toward end 62 of said valve. Pressure from line P is thus introduced to line K, and line I communicated with the atmosphere, freeing the clutch lever 86. The lever is raised by mechanism in the sewing machine in known manner at the conclusion of a stitching cycle, it being thus observed that the timing of the actuation of bleed valve 66a is not critical since the tripping thereof merely frees lever 86 and does not actuate the latter.

When the lever 86 is raised at the conclusion of the stitching cycle, the contacts 88, 89 of microswitch 87 are opened, by engagement of an extension of moving contact 88 with a portion of the lever. Solenoid 90 is thus de-energized, releasing the armature which, under the influence of spring 94, is shifted downwardly again, connecting line L to the pressure line P and line M to the exhaust. Piston 98 is thus lowered in cylinder 97 and through the medium of presser foot lever 99, the presser foot 40 is raised. The raising of presser foot releases the finger or lever 56, freeing the carriage 13 for movement to the next station.

The operating sequence aforesaid is repeated as each stop 20 engages lever 50.

It will be readily understood from the foregoing description that the device assures accurate synchronization of the movements of the pressure foot and the initiation of the stitching cycle. More specifically, the device assures that the stitching cycle cannot be commenced prior to the clamping of the garment by the presser foot or work clamp, thus preventing costly and dangerous needle fracture which often resulted if these operations were not synchronized.

The device of the present invention is not limited to use with the specific button sewing machine shown, but may be used with other stitching devices, such as button hole sewing devices or the like, wherein accurate coordination between the stitching and the operation of the presser foot is required.

Having thus described the invention and illustrated its use, what is claimed as new and is desired to be secured by Letters Patent is:

1. An automatic stitching device for performing spaced stitching operations comprising, in combination with a stitching machine including a work clamp member, a stitching machine actuator lever shiftable progressively between inoperative, intermediate and operative positions for initiating in said operative position a stitching cycle of said machine, said machine including a control cam progressively shifted during the stitching cycle, a motorized work holder carriage movable adjacent said clamp member, stops on said carriage, normally closed bleed valve means in the path of movement of said stops, first and second operating cylinders for operating said actuator lever and work clamp, respectively, said cylinders having pistons shiftable to operative and inoperative positions thereof, a source of air under pressure, conduit

means including an interposed, an adjustable valve member connecting said source to said first control cylinder and arranged to shift the piston of said first cylinder from the inoperative to the operative position thereof at a controlled rate governed by the adjusted position of said adjustable valve member responsive to the opening of said control valve means by said stops, and second valve means operated responsive to movement of said actuator lever from the inoperative to the intermediate position thereof and arranged to communicate said second cylinder to said source and shift the piston of the second cylinder to operative position in advance of the movement of said actuator lever from the neutral to the operative position thereof, and means on said cam for releasing the piston of said first cylinder to the inoperative position thereof at the completion of a stitching cycle.

2. An automatic stitching device for performing spaced stitching operations comprising, in combination with a stitching machine including a work clamp member, a stitching machine actuator lever shiftable progressively between inoperative, intermediate and operative positions for initiating in said operative position a stitching cycle of said machine, said machine including a control cam progressively shifted during the stitching cycle, a motorized work holder carriage movable adjacent said clamp member, stops on said carriage, normally closed control valve means in the path of movement of said stops, first and second pneumatic actuator means for operating said actuator lever and work clamp, respectively, adjustable flow regulator means connected to said first actuator means, a source of air under pressure arranged to be communicated to said first pneumatic actuator means responsive to engagement of said control valve means with a stop, second control valve means actuated responsive to movement of said lever from said inoperative to said intermediate position, said second valve means being arranged to communicate said second actuator means to said source, said regulator means being adjusted to admit air to said first actuator means at a rate to assure actuation of said second actuator means and thereby said work clamp prior to the shifting of said lever from said intermediate to said operative position.

3. A device in accordance with claim 2 and including means on said cam adapted to relieve said pneumatic actuator means at the completion of a stitching cycle.

4. In an automatic stitching device including a sewing machine having an actuator lever, a control cam and a work clamp, a carriage shiftable adjacent said clamp and including stop means, control means for progressively actuating said clamp and then said lever comprising pneumatic means including a valve positioned in the path of and actuated by engagement with said stop means for urging said lever to the sewing machine actuating position at a controlled slow rate, second pneumatic means including a valve operatively associated with said lever and arranged to be opened responsive to movement of said lever and in advance of the shifting of said lever to said actuated position, said second pneumatic means being adapted to shift said work clamp to operative position upon opening of said valve.

5. An automatic stitching device for performing spaced stitching operations comprising, in combination with a stitching machine including a presser foot for clamping work at the start of a stitching cycle, an actuator lever shiftable progressively between inoperative, intermediate and operative positions, to initiate a stitching cycle and a control cam progressively shifted during the stitching cycle, a support base on which said device is mounted, a motorized work holder carriage movable adjacent said presser foot, stops on said carriage, normally closed control valve means in the path of movement of said stops, a source of air under pressure, first and second control cylinders for operating said actuator lever and presser foot, respectively, said cylinders having pistons shiftable to operative and inoperative positions thereof, conduit means including an interposed adjustable valve member

connecting said source to said first control cylinder and arranged to shift the piston of said first control cylinder from the inoperative to the operative position thereof at a controlled rate governed by the adjusted position of said valve member responsive to opening of said control valve means at the completion of a stitching cycle, second valve means operated responsive to movement of said lever to the intermediate position thereof arranged to shift the piston of said second control cylinder to the operative position thereof in advance of the movement of said actuator lever from the intermediate to the op-

erative position thereof, and means on said cam for bleeding said cylinders.
